(57) CLAIM

I claim the ornamental design for a portion of a suction nozzle for a floor care appliance, as shown and described.

DESCRIPTION

FIG. 1 is a front perspective view of a portion of a suction nozzle for a floor care appliance showing my new design; FIG. 2 is a top view thereof; and, FIG. 3 is a front view thereof.

The portions shown in dashed lines are shown for illustrative purposes only and form no part of the claimed design.
